AUTOMATIC DRYING DEVICE FOR INKED SHEETS

Henry M. Kannee, Washington, D. C.

Application June 28, 1935, Serial No. 28,795

4 Claims. (Cl. 198—213)

The object of the present invention is to provide a device for receiving freshly inked sheets from a stencil applying device or a printing or lithographing device and which will hold successive sheets apart and carry them from a reception point to a discharge point, the time lag enabling drying of the ink so that when the sheets leave the apparatus and are superposed, they will not blur or offset on the reverse side of the sheets.

10 The specific object of the invention is to improve upon the device of my Patent No. 1,883,795 of October 18, 1932, particularly in the provision of a simplified form of gravity conveyor and means for adjusting the conveyor.

15 The invention will be described with reference to the accompanying drawings in which

Fig. 1 is a view in side elevation of an embodiment of the invention, partly broken away.

Fig. 2 is a plan view of the device.

20 Fig. 3 is a sectional elevation taken on the line 3—3, Fig. 1.

Fig. 4 is a horizontal section on the line 4—4, Fig. 1.

25 Fig. 5 is a vertical section on the line 5—5, Fig. 4.

Fig. 6 is a fragmentary vertical section on the line 6—6, Fig. 2, somewhat enlarged.

In the embodiment shown in the drawings, I have provided a frame comprising four tubular uprights 1 rising from base members 2 and supporting a lower horizontal frame (Fig. 4) comprising parallel frame members 3 joined by transverse frame members 4, a sleeve 3x being carried by each frame member 3, each sleeve being mounted upon one of two opposed frame members 5. Each frame member 5, at its end, is fitted within a lateral boss 6x of a sleeve 6 adjustably mounted on one of the uprights 1, set screws 7 or equivalent means being provided for holding the frame in its adjusted position relatively to the uprights 1.

40 One of the sleeves 3x has cast therewith a laterally and downwardly extending arm 3xx formed at its lower end with a horizontal bearing aperture to receive a shaft 8, one end of the shaft having mounted thereon a sprocket 9 and the opposite end carrying a bevelled gear 10 in mesh with a bevelled gear 11 on a shaft 12.

Above gear 11 and cast integrally therewith, or 45 formed separately and secured thereto, is a gear 13. Shaft 12 rotates about a bearing 14 mounted in boss 15 of frame member 3.

Opposite boss 15 on frame member 3 is a similar boss 16, and the second frame member 3 is 50 formed at each end with similar bosses 17 and 18,

boss 16 having rotatably mounted therein a shaft 19 carrying a gear 20, boss 17 having rotatably mounted therein a shaft 21 carrying gear 22 and boss 18 having rotatably mounted therein a shaft 23 carrying a gear 24.

5 Each of transverse frame members 4, intermediate its end, is formed with an apertured boss 25 receiving shafts 26 carrying intermeshing gears 21, 27x, gear 27 being also in mesh with gears 13 and 24, whereas, gear 27x is in mesh with gears 20 and 22.

When shaft 8 is rotated, the interconnecting gear system will rotate shafts 19 and 12 in opposite directions, shaft 21 in the same direction as shaft 19, and shaft 23 in the same direction as shaft 12.

Each of uprights 1 is received within the vertical aperture of an elbow connector 28, the horizontal apertures of the elbows receiving longitudinal top frame members 29 which may be tubular in form, the said frame members receiving and supporting the end sleeves 30 of a bracket comprising the parallel arms 31 and the transverse arms 31x. Inwardly spaced from but adjacent sleeves 30, each arm 31 is formed with an enlargement 32 having a central aperture internally flanged at 32x, Fig. 6, to receive an anti-friction bearing 33, which, in turn, receives the upper end of the vertical extension 34x of a spiral feeding member 34, the latter being threaded at its top to receive a nut 35, and preferably being flanged immediately below the bearing 33, as shown at 34xx. The anti-friction bearing may be covered by a cap plate 33x.

It will thus be seen that four spiral conveyors 35 are rotatably supported in the top frame, and each of these conveyors at its lower end, is secured to one of the four power driven shafts 12, 19, 21 and 23, as in the manner illustrated in Fig. 3, wherein the rod-like lower extension of the two conveyors therein shown, is projected through a horizontal aperture of shaft 12 or shaft 19, as the case may be. In practice, the conveyor will be held within the aperture by heading its end or by soldering or by any other suitable means.

45 Each spiral conveyor, illustrated in the drawings, is formed of a continuous length of relatively heavy steel or alloy wire, as, for example, vanadium, nickel-chrome wire, and preferably of non-rusting qualities and substantially resistant to elongation by its own weight.

Inasmuch as the lower frame may be bodily moved on the uprights 1, as, for example, by loosening thumb screws 7, the distance between 50

55 55

the convolutions of the four conveyors may simultaneously be adjusted by elongation, or the reverse action, secured through said movement of the lower frame.

5 As heretofore stated, shafts 19 and 21 rotate in the same direction, and shafts 12 and 23 rotate in the same direction, but opposite to 19 and 21, and the spiral conveyors will have the same directions of rotation. It will thus be 10 seen that when the spiral conveyors are rotated, each in the direction indicated by the small arrow applied thereto in Fig. 2, a sheet laid upon all four conveyors at the top thereof, not only follows the convolutions of the conveyors from the 15 top to the bottom thereof, through the action of gravity, but will tend to be moved in the direction of the arrow *a*, or, to the right of the said figure.

At the base of the said conveyor system and to the right of the frame, I place a receiving 20 tray 36 and the tendency of the rotational movement of the conveyors to eject the sheet, may be aided by an angularly extending guide bar or rod, as indicated at 38, Figs. 1 and 2, as disposed toward the base of the conveyor system opposite 25 tray 36.

As the sheets move downwardly, they are guided 30 by a plurality of vertical, preferably curved, thin metal guides indicated at 31. At the discharge or rear end of the machine may be vertically placed a polished thin metal abutment bar 39, the lower end of which will lie above the tray 36 so as to permit the discharge of the sheets 35 successively at the proper point.

At the top of each spiral conveyor, the initial 35 convolution has placed thereon a spiral formed blade, each blade being made as a disk cut from axis to periphery and one side of the cut gradually deflected, axially, until that portion of the blade at the opposite side of the cut lies at a 40 lower level to follow the spiral form of the wire conveyor. These blades may be made in the same manner as described in my aforesaid patent.

In the use of the device, it will be placed in 45 register with the stencil machine, printing press or other ink-applying device, from which the successive sheets are fed and the rotation of

the spiral conveyors will be synchronized with the feeding of the sheets to the device, one sheet passing from the spiral blades to the next succeeding convolutions of the conveyors prior to the receiving of a second sheet, and the sheets being automatically discharged into the tray at the base of the device in like timing.

It will be understood that various modifications may be made in the form and arrangement of the elements illustrated in the drawings without departing from the spirit of the invention; what I claim and desire to secure by Letters Patent, being as follows:—

1. In drying devices for inked sheets, a plurality of spaced vertical shafts, a spiral wire carrier connected to each shaft for rotational movement therewith, a spirally turned blade carried by each wire carrier and adapted to receive an inked sheet, the carrier being adapted to permit gravitational movement of a sheet from an upper 15 point thereof to a lower point thereof, and means for rotating the shafts in synchronism.

2. In drying devices for inked sheets, a plurality of spaced vertical shafts, flexible sheet supporting means on each shaft, spiral in form, 20 and adapted to permit gravitational movement of a sheet from an upper point to a lower point relatively to the shafts, means for rotating the shafts in synchronism, and means for adjusting the length of each spiral carrier to vary the 25 spacing of the convolutions thereof.

3. A device constructed in accordance with claim 1, including means for relatively adjusting the position of the lower and upper stub shafts to increase or decrease the distance between 30 them.

4. In drying devices for inked sheets, a plurality of spiral wire conveyors, an upper frame member and means for rotatably connecting the conveyors to said member, a lower frame member and means for rotatably connecting the conveyors thereto, means for relatively adjusting the frame members to increase or decrease the distance between them, and means for rotating the spiral wire conveyors.

HENRY M. KANEE.
